UNITED STATES PATENT OFFICE.

ANSON C. MILLS, OF JACKSON, MICHIGAN.

FEEDING MECHANISM FOR WIRE-FENCE MACHINES.

1,146,195.

Specification of Letters Patent. Patented July 13, 1915.

Original application filed April 13, 1912, Serial No. 690,566. Divided and this application filed March 7, 1913. Serial No. 752,645.

To all whom it may concern:

Be it known that I, ANSON C. MILLS, a citizen of the United States of America, residing at Jackson, in the county of Jackson 5 and State of Michigan, have invented certain new and useful Improvements in Feeding Mechanism for Wire-Fence Machines; and I do hereby declare the following to be a full, clear, and exact description of the invention, such as will enable others skilled in the art to which it appertains to make and use the same.

My present invention relates to wire fence-making machines, particularly to the machine of that character described in my pending application No. 690,566 filed April 13, 1912, from which the subject-matter of this present application is divided, by requirement of the Patent Office. The object 20 of my present invention is to provide improved feeding mechanism for such machines, which shall feed a continuous wire to the mechanism by which it is formed into fasteners or so-called "staples" for securely 25 fastening together the crossing wires (the "line" wires and "stay" wires); and also to provide such a feeding mechanism which shall be simple and economical in construction and operation; to provide various 30 proved features in such feeding mechanism, hereinafter appearing; to provide an improved guiding device for such wire intermediate the feeding mechanism and the staple-forming machine; to provide various 35 proved features in such guiding device hereinafter appearing. These objects are attained by, and the invention finds a preferable embodiment in, the structure herein- 40 after described and illustrated by the accompanying drawings, in which:—

Figure 1 is a side elevation, partly in vertical section, of certain operative parts of such a wire fence-making machine with my feeding mechanism and guiding device applied thereto; Fig. 2 is a side elevation of a part of the reverse side thereof, illustrating the power-carrying connections whereby my feeding mechanism is operated by a moving part of said machine; Fig. 3 is a like view, 45 enlarged, of the principal parts of my feed-

ing mechanism viewed oppositely to Fig. 1; Fig. 4 is a front view of such parts; Fig. 5 is a vertical section of parts shown in Fig. 4 taken on line 5—5 of said figure; Fig. 6 is a detail plan of part of the wire guiding device with a portion of its supporting member broken away; Fig. 7 is a side view of the same, the supporting member appearing in vertical section; Fig. 8 is a side elevation (parts being shown in vertical section) of 60 portions of the feeding mechanism at the end of its feeding movement, together with parts of the wire guiding device shown in vertical section; and Fig. 9 is a side elevation of the same and illustrating the feeding 65 mechanism at the beginning of its feeding movement.

The frame 1 carries on its upper portion the "staple"—or fastener—forming mechanism, etc. of my said wire fence-making machine to which my present invention, the wire feeding mechanism and guiding device, is applied. This staple-forming mechanism, designated generally by the reference numeral 2 is no part of my invention sought 70 to be patented pursuant to this present application and therefore will not be described hereinafter, and is shown merely for the purpose of illustrating the connection of my said present invention with such parts. 75

My wire feeding mechanism is operated by any suitable moving part of the general fence-making machine, as by its main driving shaft 3 actuated by any suitable means, as a crank or eccentric not shown, the pitman 4 connected to the crank arm 5 on the rock shaft 6 carrying the crank arm 7 whose pivoted link 8 by its connection with the wire-feeding lever 9 moves the same upward to feed a staple length of the continuous 80 wire 10 into the staple-forming machine indicated at 2.

To grip the wire and carry the same upward, the movable end of the arm 9 is provided with a bracket 14 having a limited 95 vertical movement on the arm, being held on the arm by a bolt slidable in a slot 30 in the bracket. (See Fig. 5.) On this bracket is a fixed gripper 17 and a movable gripper 16 pivoted on a stud 13 and having an arm 12 100

having its end 11 within a recess 15 in the arm 9, whereby this gripper 16 is engaged with the wire on the upward or feeding stroke of the arm, and disengaged from the 5 wire on the downward or back stroke of the said arm, during which latter movement the wire is held by a fixed gripper 28 on a bracket 18 and a gripper 27 pivoted to said bracket at 25 and having an arm 23 engaging a recess 26 in a fixed beam 19 on which the bracket 18 is slidably mounted by a bolt 31 slidable in a slot 29 in said bracket.

To shift the bracket 18, it is connected to the bracket 14 by a bar 20 pivoted to the 15 bracket 14 and slidable on an upwardly projecting arm 21 on the bracket 18 and held in contact therewith by a bolt extending through both of the same, and through a clamp 38 provided with an oil cup. On this 20 bolt is a spring 22 whereby the friction between the parts 20 and 21 can be adjusted to be greater than that of the brackets on the arm and beam. The brackets are thus first shifted, and then the bar 20 slides on the 25 arm 21 throughout the balance of the movement of the arm 9. On the upper or feeding stroke, the grippers on the bracket 14 first take hold of the wire, the bracket 18 then rises, opening the grippers thereon and leaving the wire free to rise with the further 30 movement of the arm 9. On the down stroke of the arm 9, the grippers are first reversed whereby the grippers on the bracket 18 are first closed to hold the wire and then 35 the grippers on the bracket 14 are opened to let the wire run freely therethrough.

To prevent bending the wire 10, two telescopic tubes 35 and 36 are provided through which the wire is fed, one tube being carried 40 by a collar 33 on the bracket 14 and yieldable laterally therein, the other tube being carried on a fixed beam 37 and likewise yieldable in the same.

To determine the length of the wire to be 45 fed, the rod 4 is slotted where connected to the arm 5 whereby there is lost action at the lower position of the arm 9 and the arm rests on an adjustable screw 31 (see Fig. 3.) whereby the downward movement of the 50 said arm is limited more or less.

From the foregoing description the operation of my invention is obvious without further explanation.

What I claim is:

55 1. In a wire fence machine, means for feeding wire, comprising a fixed member and a reciprocating member, a wire gripper mounted on each member, and means positively opening said grippers operated by movement of the reciprocating member.

60 2. In a wire fence machine, means for feeding wire, comprising a reciprocating member, a gripper carried by the same,

means operated by movement of said member for positively closing said gripper during the forward movement of said member and for positively opening said gripper during the opposite movement of said member. 65

3. In a wire fence machine, a fixed member and a reciprocating member, a gripper 70 on each member, means operated by movement of the reciprocating member for alternately and positively opening said grippers.

4. In a wire fence machine, a fixed member and a reciprocating member, a gripper 75 on each member, means for positively and alternately opening and closing said grippers operated by movement of the reciprocating member, whereby the gripper on the fixed member is open and the gripper on the 80 reciprocating member is closed, while the movable member is moving in one direction and the grippers reversed when said member is moving in the opposite direction.

5. In a wire fence machine, means for 85 feeding wire, comprising a stationary beam, a reciprocating beam, a bracket movably mounted on each beam, a wire gripper on each bracket, each gripper opened and closed by the movement of the bracket on the beam, 90 and means for simultaneously moving the brackets on the respective beams to alternately open and close the grippers.

6. In a wire fence machine, wire feeding mechanism, comprising a stationary beam, a 95 reciprocating beam operated by the machine, brackets on the respective beams, each having a limited sliding movement thereon, a wire gripper on each bracket connected to the respective beam, and means for simultaneously sliding the brackets on the beam to alternately open and close the grippers. 100

7. In a wire fence machine, means for feeding wire, comprising a fixed beam, a reciprocating beam, a bracket slidably mounted 105 on each beam, connecting members extending between the brackets and slidable on each other, means for adjusting the frictional engagement of said members, a gripper mounted on each bracket, each gripper 110 having an arm engaging the respective beam to alternately open and close the grippers.

8. In a wire fence machine, a fixed beam and a reciprocating beam, a bracket slidably mounted on each beam, a gripper mounted 115 on each bracket, each gripper having an arm engaging a recess in the respective beam, slidably overlapping means connecting the brackets, and an adjustable spring to force 120 said means into frictional contact whereby the brackets are shifted on the beams at the beginning of the movement of the reciprocating beam.

9. In a wire fence machine, a fixed beam, a reciprocating beam, a bracket on each beam 125 having limited sliding movement thereon, a

wire gripper on each bracket consisting of a fixed member and a pivoted member, each pivoted member having an arm engaging a recess in the respective beam, and means for simultaneously shifting the brackets on the beams at the beginning of the movement of the reciprocating beam.

In testimony whereof I affix my signature in presence of two witnesses.
